SHOE SHINE APPARATUS WITH STAND

Robert C. Randolph, 2300 19th St., NW.,
Washington, D.C. 20009

Filed June 4, 1973, Ser. No. 366,293

Term of patent 14 years

Int. Cl. D6—06

U.S. Cl. D86—12

FIG. 1

FIG. 2

FIG. 3

FIG. 4

FIG. 1 is a side view of the shoe shine apparatus with stand showing my new design, the opposite side having the same appearance;

FIG. 2 is a front view of the shoe shine apparatus with stand of FIG. 1;

FIG. 3 is a top view of the shoe shine apparatus with stand of FIG. 1;

FIG. 4 is a rear view of the shoe shine apparatus with stand of FIG. 1;

FIG. 5 is a perspective view of the shoe shine apparatus with stand of FIG. 1; and

FIG. 6 is an enlarged view of a portion of the surface of the platform of the shoe shine apparatus with stand of FIG. 1.

I claim:

The ornamental design for a shoe shine apparatus with stand, as shown.
